UNITED STATES PATENT OFFICE.

EDWARD C. BALDWIN, OF BOSTON, MASSACHUSETTS.

FOLDING DRINKING-CUP.

1,129,778.

Specification of Letters Patent. Patented Feb. 23, 1915.

Application filed May 11, 1912. Serial No. 696,662.

To all whom it may concern:

Be it known that I, EDWARD C. BALDWIN, a citizen of the United States, and resident of Boston, in the county of Suffolk and 5 State of Massachusetts, have invented certain new and useful Improvements in Folding Drinking-Cups, of which the following is a specification.

This invention relates to drinking cups 10 made of flexible waterproof sheet material such as paraffin paper having flat sides which normally lie in contact with each other and are adapted to be bulged outwardly to open the mouth of the cup.

15 The invention has for its object to provide an improved construction whereby the mouth of the cup may be conveniently opened for use without the necessity of introducing the fingers into the mouth of the 20 cup, the construction being such that strength and durability of the cup are insured.

A further object is to provide a collapsible cup having a handle to facilitate its use.

25 The invention consists in the improvements which I will now proceed to describe and claim.

Of the accompanying drawings: Figure 1 is a plan view of a preferred form of blank 30 from which the cup is made. Fig. 2 is a perspective view of the completed cup in flat condition. Fig. 3 is a perspective view of the cup, the mouth being open for filling. Fig. 4 is an end view of the cup when flat, 35 as shown by Fig. 2. Fig. 5 is an end view of the cup when opened as shown by Fig. 3. Fig. 6 is a plan view of the lower portion of another or modified form of blank. Fig. 7 is a side elevation of a completed cup made 40 from a blank, the lower edge of which is formed as in Fig. 6. Fig. 8 represents a section on line 8—8 of Fig. 7. Figs. 9, 10 and 11 represent respectively sections, slightly enlarged, on lines 9—9, 10—10, and 11—11 45 of Fig. 7.

The same reference characters indicate the same parts in all the figures.

Referring first to Figs. 1 to 5 inclusive, I 50 form from suitable waterproof flexible material such as paraffin paper, a blank of the general form represented by Fig. 1, the said blank when folded along the longitudinal lines x , x , and y , y , forming a flat tube composed of a continuous side piece 12, and two

members 13 and 14 which overlap each other 55 along the central portion of the flat tube and form a pieced side.

When the blank is converted from the form shown in Fig. 1 to the form shown in Fig. 2, by suitable folding mechanism, the 60 overlapping portions of the members 13 and 14 are caused to adhere by means of a coating of suitable adhesive first applied to one or both of the surface portions of said members that are brought together by such 65 folding, the pieced side thus having a closed seam or joint. The member 13 is extended to form a flap 15 which is free from cement and is adapted to be turned outwardly to 70 form a fin handle, as indicated by Fig. 3. One end of the continuous side 12 is extended to form a flap 16, the length of the body portion of which is practically equal 75 to the width of the continuous side 12. After the members 13, 14 have been folded inwardly and overlapped, a line or stripe of glue or cement is applied along the upper portion of the flap 16 and also along the edges 80 of the members 13 and 14 which have been folded down against the side 12. In other words, the cement or glue is applied along 85 the portion of the bottom of the cup which is then open, some of the glue or cement extending on to the surfaces of the paper both sides of the open bottom. After this, the 90 bottom of the cup is folded up, as indicated in Fig. 2, the line of the fold being some little distance above the lower edge of the 95 portions of the members 13 and 14 so that when the blank is then pressed as by being run between rollers, the glue or cement is squeezed slightly into the open but folded up edge of the cup and is also squeezed in the other direction toward the edge of the flap 16. Inasmuch as the lower end of the cup is folded 100 along the transverse line just described, such folding results in the formation of a barrier which prevents the glue or cement from being squeezed up into the inside of the lower portion of the completed cup. This 105 folding up of the bottom portion of the cup reinforces and stiffens it, the extreme lower edge of the cup then possessing four thicknesses throughout the greater extent of the transverse area of the bottom, and five thicknesses at substantially the middle of the folded bottom. It will now be seen that the blank shown by Fig. 1 is converted into a

flat sided cup having a closed body formed by the overlapped and cemented portions of the members 13 and 14 of the pieced side, and a closed bottom formed by the cementing of the flap 16 to the pieced side. The continuous side 12 of the cup is elongated to form a drinking lip 12^a. When the cup is filled, liquid can be conveniently taken therefrom over the lip 12^a, the stiffened and reinforced lower edge of the cup enabling it to be conveniently and securely held even without use of the flap or fin handle 15.

As shown by Fig. 2, the sides of the cup are normally flat and practically in contact with each other. The mouth or open end of the cup may be opened by bulging the sides of the cup outwardly, this being accomplished by pressure of the thumb and fingers of one hand on the narrow necks 18 formed by folding the blank along the lines *x*, *y*. The free flap 15 enables the thumb and a finger of the other hand to exert an outward pull on the side of the cup from which said flap projects, thus facilitating the outward bulging of said side, the flap constituting a handle.

Referring to Figs. 6 to 11 inclusive, it will be seen that the structure is substantially the same as above described with the exception of the formation of the lower edge portions of the cup which constitute the reinforced bottom. In this last illustrated cup, the flap 16 has relatively narrow end portions 16^a which are formed on and constitute extensions of the corresponding end portions of the members 13 and 14 and are narrower than the body portion of the flap. The central portion of the flap 16 is provided with a wing 16^b, the base of which is partially separated from the body portion of the flap by an incision 17. Prior to the folding operation above described the flap 16, its extensions 16^a and wing 16^b are coated with cement, the cement coated area being indicated by the shading, Fig. 6. The operation of folding the blank along the lines *x*, *y*, causes the extensions 16^a to bear on the body portion of the flap 16, as indicated by Fig. 7. The flap 16 is next folded against the outer surfaces of the members 13 and 14 constituting the pieced side, the flap 15 being at this time folded back against the member 13, and the wing 16^b being caused to bear on the lower end portion of said flap, and on the adjacent portion of the member 14, as indicated by Fig. 7. It will now be seen that the blank shown by Fig. 6 is converted into a flat sided cup having a closed body formed by the overlapped and cemented portions of the members 13 and 14 of the pieced side, and a closed bottom formed by the cementing of the flap 16 to the pieced side. The extensions 16^a reinforce and strengthen the corners of the cup at its closed end or

bottom and the wing 16^b reinforces and strengthens the lower end of the longitudinal flap 15.

It sometimes happens that when a cup has been carried in a folded condition in a pocket its sides become curved, one of the sides curving inwardly and the other outwardly. When the sides are thus curved, pressure on the necks 18 will be liable to bulge or bend both sides in the same direction without opening the mouth of the cup. The provision of the free flap or handle 15 enables the mouth of the cup to be quickly and conveniently opened and prevents both sides from being bent or bulged in one direction. The location of the flap 15 on the exterior of the cup renders the insertion of the operator's fingers into the mouth of the cup for the purpose of opening the same unnecessary. The flap or handle 15 enables the operator to manipulate the cup when it is charged with water.

It is not necessary for the operator to press inwardly on the necks 18 in opening the mouth of the cup. The operator can open the mouth by pressure of the finger which grasps the flap 15 against the adjacent side of the cup. Another method of opening the cup without necessitating the placing of a finger inside thereof is by the action of the water itself with which it is desired to fill the cup. As shown in the drawings, one of the sides of the flat cup is longer than the other side and forms a projecting lip 12^a. In other words, the side of the cup which is provided with a handle is of less length than the side 12 and consequently if the cup be held somewhat inclined under a descending jet or stream of water so that such jet or stream will strike the lip 12^a of the side 12, the action of the water will automatically open the cup. By a similar action, the cup may be opened even when dipping water from a spring or elsewhere. If the cup be simply dipped into the water and then raised with the side 12 undermost, the weight of the water will open the cup and fill it.

The cup is vertically elongated; that is, its depth is greater than its width or diameter. As will be readily understood, there are many advantages in this form as distinguished from a wide shallow cup; for instance, it can be more readily accommodated in the pocket, and there is less liability of spilling liquid, especially in a railroad train. The use of such a cup is greatly facilitated by having a handle which reaches sufficiently to both the upper and lower portions of the side which carries it, to steady the cup when filled so as to avoid risk of its accidental tilting due to its vertical elongation, and also to control the gradual tilting according to the rapidity of drinking by the user. As the handle is flexible

and normally lies flat against the side of the cup when the latter is collapsed, it takes up practically no additional room or space, and does not interfere with the flexibility 5 of the cup when in the pocket. But when opened out, it not only steadies the cup in use, as mentioned, but enables the cup to be filled and emptied without inclosing it or surrounding it with the fingers, thus leaving 10 the walls free to be held distended by the contained liquid and avoiding risk of causing overflow by collapsing pressure of such fingers.

The projecting lip 12^a, when the cup is 15 filled, immediately becomes curved laterally because it must conform to the change of shape of the side 12, as shown by Fig. 3. It is therefore strengthened by assuming such curved shape and reliably serves to 20 conduct water to the mouth of the user. Owing to the fact that said lip, as well as the entire cup, is waterproof, it does not soften or lose its stiffness when wet, and consequently the cup can be used many 25 times without liability of the lip doubling or bending over. In other words it can be dipped in water, or held under a spout, or used to drink from, many times, without losing its capability of being converted to 30 spout form and used in that form.

In each form illustrated and described, the cup is provided with a strongly reinforced bottom which will enable the cup to be held, when filled with water, by means of 35 a finger extending under the bottom of the cup, even without grasping the fin handle, such strengthening or reinforcing preventing the lower edge from being cracked or broken against the pressure of the supporting finger, by the weight of the fluid contents of the cup.

I claim:—

1. A vertically elongated waterproof 45 flexible cup normally flat and having an elongated flexible handle normally flat against a side of the cup, extending from its upper to its lower portion to steady the cup in use.

2. A vertically elongated waterproof 50 flexible cup normally flat and having an elongated flexible handle normally flat against a side of the cup, extending from its upper to its lower portion to steady the cup in use, said cup having the side which 55 carries the handle shorter than the other side, whereby a lip or extension of said other side is adapted to receive pressure of water to effect the opening of the cup when held by said handle.

3. A drinking cup composed of a sheet 60 of water-repellent flexible material, folded to be normally flat, and adapted to be distended to hold liquid, said sheet having a free integral edge forming a flap to constitute a flexible handle adapted to lie flat 65 against the body of the cup when collapsed, and to be turned outward for use.

4. A drinking cup composed of thin flexible material creased at its side edges to produce overlapped edges forming the entire 70 back, said overlapped edges being secured together, a projecting flap from one of said edges, said flap being bent outward to form a handle, and a fold overlying said overlapped edges to form a bottom for the cup. 75

5. A drinking cup composed of thin flexible material creased at its side edges to form overlapping parts constituting the back of the cup, a flap overturned from the front of the cup and overlying the back, means for 80 securing all of said flaps together, and a lip projecting from one edge of the overlapped back pieces to constitute a handle.

6. A vertically elongated waterproof 85 flexible cup normally flat and having a flexible handle normally flat against a side of the cup, extending from the upper portion of the cup sufficiently far down the side thereof to steady the cup in use.

7. A flat cup of flexible material, having 90 one of its sides at the open end permanently longer than the other side, the longer side forming a lip adapted to be stiffened by assuming a transversely curved form when the cup is distended, the said material being 95 of a waterproof character to prevent said lip from softening and changing its spout shape when in use, the seam portions of the cup being capable of resisting attack by moisture. 100

8. A flat cup of flexible material provided with permanently secured seam portions, the material being of a waterproof character to prevent the seam portions from being attacked by moisture, the two sides of the 105 cup being of unequal length to present a lip adapted to be stiffened by assuming a transversely curved form when the cup is distended, the waterproof character of the material preventing softening of the lip by 110 water.

In testimony whereof I have affixed my signature, in presence of two witnesses.

EDWARD C. BALDWIN.
